UNITED STATES PATENT OFFICE

93,293

DESIGN FOR A RAILWAY CAR SEAT

Louis F. Scott, Philadelphia, Pa., assignor to The
J. G. Brill Company, Philadelphia, Pa., a cor-
poration of Pennsylvania

Application June 14, 1934, Serial No. 52,173

Term of patent 14 years

To all whom it may concern:

Be it known that I, LOUIS F. SCOTT, a citizen of the United States, residing at Philadelphia, in the county of Philadelphia, and State of Pennsylvania, have invented a new, original, and ornamental Design for Railway Car Seats, of which the following is a specification, reference being had to the accompanying drawings, forming part thereof.

Figure 1 is a view in perspective of the car seat, showing my new design; and

Fig. 2 is a side view of the car seat of the present design, one of the seat elements thereof being shown in reclining position.

I claim:

The ornamental design for a railway car seat, as shown and described.

LOUIS F. SCOTT.
